UNITED STATES PATENT OFFICE.

EDWARD M. BENTLEY, OF BOSTON, MASSACHUSETTS.

RAILWAY-CAR.

SPECIFICATION forming part of Letters Patent No. 437,343, dated September 30, 1890.

Application filed June 19, 1890. Serial No. 356,018. (No model.)

To all whom it may concern:

Be it known that I, EDWARD M. BENTLEY, a citizen of the United States, residing at Boston, county of Suffolk, State of Massachusetts, 5 have invented certain new and useful Improvements in Railway-Cars, of which the following is a specification.

In my application Serial No. 344,079 I have shown and described a railway-car provided 10 with a laterally-movable end section, which took the form of a simple coupling-bar, or was enlarged into a platform which could be enclosed to form a vestibule.

In my present invention I have shown an 15 improvement upon my previous device, which consists of providing a railway-car with a laterally-movable end section, as in the former case, but which is placed outside of the ordinary platform. This laterally-movable end 20 section may be provided with a coupling attached directly to it, and have both a longitudinal and a lateral spring-connection with the vehicle, or it may have only a lateral movement relative to the vehicle, and the 25 coupling-bar be attached independently to the car. In the latter case the said section will be provided with a yielding surface adapted to meet a similar surface on an adjacent car. The said section may also, if desirable, be supported 30 on the end of the car without the pivoted extensions reaching under the car, which are shown in my previous application.

Referring to the accompanying drawings, Figure 1 is a side elevation of a railway-car 35 provided with my invention. Fig. 2 is a plan of the lower frame-work of the car. Fig. 3 is an end view of Fig. 2. Fig. 4 is an end view of Fig. 1. Figs. 5 and 6 represent modifications, and Figs. 7, 8, 9, 10, 11, and 12 are details.

Referring to the drawings, A represents the ordinary frame-work of the lower part of the car formed upon the sills and stringers.

B is the body-bolster of the car, carrying the king-bolt.

C is the end sill of the platform, which in this construction is carried by the two supplemental stringers D, these stringers being made heavier than those ordinarily employed.

E is a beam placed on substantially the 50 same level as C, and having a concave edge corresponding to the convex edge of C. The

beam E is attached to the stringers F, which are upheld by the bracket G, Fig. 4, being freely movable thereon by means of the friction-rollers H. The inner ends of stringers F are 55 joined together and are prolonged by a rod I, which at one end passes through the cross-piece J, between the stringers F, and is held by the oppositely-acting springs L. At the other end the rod has an eye embracing the 60 king-bolt. By this arrangement the beam or bar E has a longitudinal spring movement by means of springs L, and at the same time is free to spring laterally about the king-bolt. It is normally held in its central position by 65 means of the springs K, and is held throughout its length against vertical movement relatively to C by means of brackets M, attached to C and embracing E upon opposite sides, Fig. 12. By this means any torsional strain that 70 comes upon the bar E when connected to an adjacent bar is immediately transmitted to the sill C, and by means of upright posts O, (shown in Fig. 2,) which I shall describe at length hereinafter, is transmitted to the 75 frame-work of the car through the roof. Of course the torsional strain upon C will be partly taken up by the stringers D; but a better construction will be afforded by having the stringers D supplemented by the posts O. 80 I prefer to provide upon each end of the movable section E means for connecting it firmly throughout its length with a similar device on an adjacent car, so that any rocking tendency of one car will be transmitted to the 85 next, and a steadier movement of the two together will be attained. Such devices are shown in Figs. 3 and 4, where P represents a lug or projection upon one end of the bar E, while upon the other end there is a corresponding recess Q, upon the top and bottom of which are held under spring-pressure two plates R. Whenever the two bars E are in contact, the extension P upon one enters the recess Q upon the other, and the two bars will 90 therefore tend to move together as a whole, except so far as a limited movement is permitted by the springs S, which act upon plates R.

In the form of my invention which I have 100 thus far described the coupler T is of any ordinary construction, and its attached draw-

bar is connected to the stringers F by passing through the cross-piece J and has a slight spring movement by means of rubber buffers T'.

5 As my present invention is especially adapted for use upon passenger-cars upon which the end section may be placed outside of the ordinary platform, the bar E may serve simply as an intermediate platform to occupy 10 the space between the platforms of the two adjacent cars, or it may be provided with inclosing sides to form a covered connection between the two cars, which I herein term a "vestibule."

15 In Figs. 1 and 2 I provide two upright sides U, which are connected at the top to form the vestibule, and which are provided with hinged plates V, resting against the stationary part 20 of the car. In this case the platform will be inclosed by the posts O, and sides W, which extend from the sill C to the car-roof, and doors X will be provided at the top of the steps, which will open upward and have on 25 the inside a hand-rail Y. The steps are not shown in the drawings, but their place is indicated. When the door X is opened, the hand-rail Y will serve to assist passengers entering by the steps.

In Fig. 5 I have shown a form which in 30 some respects is preferable to the one illustrated in Figs. 1, 2, and 3. In this case the bar E has no longitudinal movement relative to the car. It is carried rigidly upon the stringers F, which are connected together at 35 their inner ends and pivoted upon the king-bolt without any intermediate springs. The draw-bar in this case swings with the bar E, and has a longitudinal spring movement, which in the former device was afforded by 40 the springs L. By this arrangement the section E is more closely connected to the sill C, having only a lateral movement relatively thereto about the king-bolt as a center. It becomes necessary in this case to provide means 45 for compensating for the longitudinal spring movement between the two adjacent cars. For this purpose I provide an end plate Z, similar to the end plate of the ordinary vestibule-car, which is connected to the main part of the 50 vestibule by a bellows, which permits the end plate to move in and out while preserving the inclosure intact. My device, however, differs from the one ordinarily employed, in that the plate Z is provided with four dowel-pins rigidly attached thereto, which slide in and out 55 of corresponding sockets in the walls of the vestibule. This is shown in detail in Fig. 8. In my device, therefore, the end plate Z will have simply a forward-and-backward movement, while in the ordinary construction it is pivoted to guide-rods, so that the two sides of the plate move unequally.

In my device it is only essential to have a simple longitudinal movement of the plate Z, 60 because all lateral movement is provided for when the whole section is moved bodily from one side to the other.

In Figs. 6, 7, 8, 9, 10, and 11 I have shown a very simple and practical form of my invention. The bar E' and the sides of the 70 vestibule U are replaced by a simple frame E', of the form shown in Fig. 9. This is formed of thin plates, and the whole is curved to correspond to the outline of C, as will be seen by reference to Fig. 7. This frame is 75 supported upon the outside of the inclosed platform by friction-rollers, as shown in Figs. 6 and 7, so that it will move freely from side to side. The frame E' is provided at the bottom with a fork which embraces the neck of the 80 draw-bar. The draw-bar being free to swing laterally in a well-known manner will always tend to carry the frame E' with it. Upon the outside of E' is placed the plate Z, with the intermediate bellows-connection, as shown in 85 Figs. 6 and 7. Between E' and Z will be placed a telescoping foot-piece B², Figs. 7 and 8.

In connection with the device described, I intend to employ an automatic coupling for a pipe or electric conductor used to convey 90 air, steam, or electricity. The method of applying this is similar to that set forth in the prior application above referred to.

In Fig. 11 C² is an air-pipe having a pivoted end section D². This has a telescoping 95 joint and a spring-actuated tip adapted to fit in a corresponding socket on the pipe of an adjacent car. I also provide a supplementary flexible end section E², which can be used to make connection with the ordinary 100 manual coupler now employed. I prefer, however, in some cases to bring the terminal of the automatic coupler onto the plate Z instead of attaching it simply to the movable end section E. This is shown in Fig. 6. When this arrangement is employed, the air-pipe will be automatically coupled upon the meeting of two cars, and the couplers themselves may always be accessible for inspection. It will also do away with the flexible tube covered 105 with rubber or other perishable material now employed.

What I claim as new, and desire to secure by Letters Patent, is—

1. The combination, with a railway-car, of 115 an inclosed entrance-platform stationary with respect to the car, and an end section external to the platform having a lateral movement relatively to the car for adjustment on curves, and provided with a longitudinally-yielding end surface for meeting a similar device on an adjacent car.

2. The combination, with a railway-car having an inclosed end platform and steps leading therefrom, of a laterally-movable frame 125 outside the platform and provided with yielding extensions maintaining the end of the platform closed, and an end plate adapted to meet a corresponding plate on an adjacent car, and having a longitudinally-yielding connection with the said frame by which it is 130 caused to move laterally therewith while adjusting itself to a similar device on an adjacent car.

3. The combination, with a railway-car, of an end section outside the platform placed on bearings at top and bottom so as to move freely from side to side, and provided with a yielding end plate having a flexible connection with the main frame of the section, the said section being also provided with flexible connections to the car, maintaining the end of the platform closed during lateral movement. 5
10. 4. The combination, with a railway-car, of an end section outside the platform of the car provided with a yielding surface for meeting a similar device on an adjacent car, and having bearings by which it is movable laterally relatively to the car, and a draw-bar having a longitudinally-yielding connection with the car independent of the connection between the car and the end section. 15
5. The combination, with a railway-car, of a laterally-swinging draw-bar and an end section placed on bearings outside the platform of the car and so connected to the said draw-bar as to move laterally therewith. 20
6. The combination, with a railway-car, of an inclosed end section supported on the car-body by bearings permitting movement about a center and having a longitudinally-yielding surface adapted to meet a similar device on an adjacent car, the said section being on a line with the car-floor, and the car having a draw-bar extending beneath the said section and swinging laterally correspondingly therewith. 25
7. The combination, with a railway-car, of an inclosed end section supported on the car-body by bearings permitting movement about a center and having a longitudinally-yielding surface adapted to meet a similar device on an adjacent car, a central coupler beneath the said section, and side-engaging device for connecting the section to a section of an adjacent car. 30
8. The combination, with a railway-car, of a laterally-movable end section outside the car-platform and connected thereto along its length, means for coupling the said section to a similar device on an adjacent car, and posts extending from the edge of the car-platform to the roof-timbers, whereby the torsional strain on the platform is transmitted to the car-frame. 35
9. The combination, with a railway-car, of a conductor thereon having a movable end section connected with a similarly-movable part of the car-platform. 50
10. The combination, with a railway-car, of a conductor having a laterally-movable end section connected to a similarly-moving part of the car and provided with a supplementary flexible end section. 60
11. The combination, in a railway-car, of a conductor having a laterally-movable end section connected to a similarly-moving part of the car and provided with an automatic coupling, and a supplementary flexible end section provided with a manual coupling. 65
12. The combination, with a railway-car, of an inclosed end section having a yielding end plate and a conductor on the car having its terminals connected to the said end plate. 70
13. The combination, with a railway-car, of an inclosed end section having a yielding end plate and a conductor on the car having its terminals provided with an automatic coupling attached to the end plate of the vestibule. 75
14. The combination, with a railway-car, of a laterally-movable end section or platform supported on the end of the car by bearings permitting a lateral movement and an independently-supported draw-bar swinging laterally and adapted to engage with the said section and move therewith. 80
15. The combination, with a railway-car, of a vestibule-framing supported outside the car-platform by bearings permitting a lateral movement, and an end plate having a yielding connection with said framing and adapted to meet a similar plate on an adjacent car. 85
16. The combination, with a railway-car, of a laterally-moving end section on the car-body, a similarly-moving draw-bar beneath it, and a conductor on the car having a laterally-moving end section connected to the end section of the car and having thereon a coupling adapted to meet a similar coupling on an adjacent car. 90
17. The combination, with a railway-car, of an inclosed end platform, an upright framing supported outside the platform on centered bearings, so as to have a centered movement relative to the car, yielding connections between the said frame and the platform, an arched end plate supported from said frame, but having a longitudinal spring movement relative thereto, and a bellows connecting said end plate to said framing. 95

Signed June 14, 1890.

EDWARD M. BENTLEY.
